UNITED STATES PATENT OFFICE.

BERNARD H. LARKIN, OF CHICAGO, ILLINOIS, ASSIGNOR, BY MESNE ASSIGNMENTS, TO
CONTINENTAL CAN COMPANY, INC. A CORPORATION OF NEW YORK.

METHOD OF CUTTING NAIL-CAPS AND CAN ENDS.

1,186,917.

Specification of Letters Patent. Patented June 13, 1916.

Application filed April 24, 1909. Serial No. 492,077.

To all whom it may concern:

Be it known that I, BERNARD H. LARKIN, a citizen of the United States, residing at Chicago, in the county of Cook, State of Illinois, have invented certain new and useful Improvements in Methods of Cutting Nail-Caps and Can Ends, of which the following is a description, reference being had to the accompanying drawing and to the letters and figures of reference marked thereon.

The invention relates to new and useful improvements in the method of cutting and forming nail caps and can ends, having a central opening therein, from sheet metal.

An object of the invention is to provide a method of utilizing the waste material cut out in forming the central opening in a can end to form nail caps, and to expedite the making of the nail caps.

Prior to my invention, it has been customary to take the disks cut out in forming the central opening in can ends and to feed these disks one by one to a suitable machine for forming nail caps. By my improved method, the nail caps are all formed prior to cutting out of the waste material so that when the waste material is cut out, the nail cap is completed.

In the drawings: Figure 1 shows a sheet of metal having nail caps formed therein, also disks cut out of the waste ends of the sheet and in dotted lines, the position of the can ends, which are to be subsequently cut from the sheet. Fig. 2 is a view similar to Fig. 1, showing the sheet presented to a gang of dies and the can ends which are cut out by said gang of dies in full lines, while in dotted lines, a second presentation of a sheet to the gang of dies is indicated. Fig. 3 is a section through the sheet showing one of the formed nail caps. Fig. 4 is a plan view showing a formed can end and a nail cap formed from the waste material cut out in forming the central opening therein. Fig. 5 is a plan view of a finished nail cap.

In order that the waste material left after cutting can ends from a sheet of metal may be reduced to a minimum, said can ends are preferably arranged in rows with said can ends staggered relative to each other, in adjacent rows. This will cause the waste material to be concentrated at the ends or sides of the sheet.

In Fig. 1, I have shown a sheet of metal

A and the concentrated waste ends are indicated at 1, 1, and 2, 2. This concentrated waste material is utilized to a certain extent by cutting therefrom disks which may be shaped into any desired form. The disks which are cut out from the waste ends are indicated at 3 in Figs. 1 and 2. In order that the sheet may be better handled, to cut the disks from the waste ends, said sheet is first presented to a gang of dies for cutting the waste ends before the can ends are cut from the sheet. In forming a can end having a central opening, it has been found practicable to utilize this waste material in forming nail caps. In Fig. 5, I have shown a nail cap 4, which consists of a disk of material having its central portion raised as at 5 and perforated as at 6. These nail caps are of well known construction and further description will not be necessary.

According to my method, a nail cap 5 is formed and perforated but not cut out at the same time that the disks are cut out from the waste ends. I accomplish this result by providing a gang of dies which will shape and perforate each nail cap at the same time the waste ends are cut, as shown in Fig. 1. After each one of the nail caps has been formed, and the waste ends have been cut, the sheet of metal is presented to a gang of dies and a series of can ends 7 are cut therefrom. As herein shown the can ends of this series are arranged in parallel rows crosswise the sheet and the distance between adjacent can ends is slightly greater than twice the diameter of a can end so that in subsequent operations, other can ends may be cut therefrom by shifting the sheet or changing the sheet end for end.

While I have shown herein a particular arrangement of can ends, which is very desirable in cutting one pound can ends from a standard sheet of metal, it will be understood that from certain aspects of the invention, any desired arrangement of can ends may be followed, the essential feature being that the waste material of each can end is to be first formed into a nail cap so that when waste material is cut out to form the central opening, the nail cap will be completed.

I have shown in Fig. 2 in dotted lines, a second series of can ends 8, which are cut out by the same gang of dies by changing the sheet end for end. In the third opera-

tion by shifting the sheet sidewise, the remaining can ends shown in Fig. 1 in dotted lines, may be cut.

In Fig. 3, the lines 9, 9, indicate the line of cutting in forming the central opening in the can end. It will also be obvious that from certain aspects of the invention, the nail caps may be formed in the waste material to be cut out in forming each can cap without operating upon the waste ends to cut out the disks 3, 3, and said disks 3, 3, if cut from the waste ends may be cut in a separate operation. I prefer however, to form the nail caps at the same time as cutting the disks from the waste ends, for the reason that this saves presenting the sheet for a separate operation, and practically reduces the cost of making the nail caps to nothing, for the reason that the sheet material must be presented to a gang of dies for cutting out the disks 3 from the waste ends. While I have described my invention as especially adapted for forming nail caps, it will be obvious that from certain aspects of the invention, other articles than nail caps may be formed from the waste material cut out in forming the central opening in the can end. The essence of the invention

is in the forming of the article which is to be made from said waste material, subsequent to the cutting out of said waste material, so that in a single operation, the article is finished by cutting out the waste material and the can end is formed.

Having thus particularly described my invention, what I claim as new and desire to secure by Letters Patent, is:

The method of cutting and forming nail caps and can ends having a central opening therein from sheet metal, consisting in presenting a sheet of metal to a gang of dies and forming in one operation a nail cap in each portion of the waste material cut out in forming the central opening in each can end, presenting the sheet to another gang of dies and cutting out and shaping in a series of independent operations the can ends and cutting out the formed nail cap to form the central opening in each can end.

In testimony whereof I affix my signature, in presence of two witnesses.

BERNARD H. LARKIN.
